DOOR CHECK

George Halinka, Detroit, Mich.

Application August 29, 1935, Serial No. 38,387

5 Claims. (Cl. 292—263)

My invention relates to a new and useful improvement in a door check adapted for use in connection with swingable doors and so arranged and constructed that when the door is swung open the invention may operate to lock the door in open position and prevent its inwardly swinging to a closed position. The invention is particularly adaptable for use on barn doors, garages and the like which are subject to sudden drafts and which may be blown closed at the time that the door should be in an open position.

It is another object of the present invention to provide a door check of this class which will be simple in structure, economical of manufacture, durable, light, compact and highly efficient in use.

Another object of the invention is the provision of a door check of this class having a pair of links arranged to form a toggle constructed and arranged so that when the toggle is broken to one side for retaining the door in open position, it may be easily and quickly broken to the other side for permitting the closing of the door.

Another object of the invention is the provision of a door check of this kind so constructed and arranged as to permit the door opening to a maximum degree.

Other objects will appear hereinafter.

The invention consists in the arrangement and combination of parts hereinafter described and claimed.

The invention will be best understood by a reference to the accompanying drawing, which forms a part of this specification, and in which,

Fig. 1 is a fragmentary, sectional view through a door showing the invention applied and illustrated in top plan view.

Fig. 2 is a view similar to Fig. 1 showing the door open in dotted line position and closed in full line position.

Fig. 3 is a fragmentary, sectional view taken on line 3—3 of Fig. 1.

Fig. 4 is a fragmentary, sectional view taken on line 4—4 of Fig. 1.

Fig. 5 is a view similar to Fig. 1 showing a modified form of the invention.

In the drawing I have illustrated a portion of a door 9 swingably mounted by the hinge 10 to a stationary part 11 of the building with which the door is used. The invention comprises a bracket 13 which is attached to the inner surface of the stationary part 11 of the building. Swingably connected at one end to the outer end of the bracket 13 is a link 14, the opposite end of which is pivotally connected to a connecting plate 15. An elongated link 16 is pivotally connected at one

end to the plate 15 and at its opposite end pivotally connected to the bracket 17 which is mounted on the inner surface of the door 9. It will be noted that the link 16 is of considerably greater length than the link 14. The plate 15 is doubled upon itself as at 18 so as to overlie the adjacent ends of the links 14 and 16 and form a channel in which these ends engage and also provide an abutment for preventing the toggle so arranged from springing inwardly past center beyond a certain distance. The doubled-over portion 18 is doubled upon itself and arranged to provide the gripping portion 19 whereby the toggle may be gripped and swung outwardly past center to permit its collapse.

When the door is swung into open position the toggle will break past center as shown in Fig. 1. The closing of the door will be resisted as further breaking of the toggle past center in the direction in which it is broken is resisted by the engagement of the links 14 and 16 by the channel portions 18. In order to close the door, the gripping portion 19 is gripped and pulled outwardly so as to break the toggle past center on the opposite side, and when the door is swung to closed position, the device is in position illustrated in full lines as shown in Fig. 2.

From the description given it is obvious that the device may be very economically manufactured as all of the parts may be formed from stampings. In Fig. 5 I have illustrated a slightly modified form of the invention in which I provide a link 14' having the end 20 bent at a slight angle to the main body of the link. A link is provided which takes the place of the link 16 and comprises the elongated arcuate portion 21 and the shorter straight portion 22 to provide the bend 23. The end of the portion 21 is pivotally connected to the bracket 17' and a connecting plate 15' having the finger grip 19' is also provided. With this type of structure, the door may be swung while at the same time a tight closing of the door becomes possible.

While I have illustrated and described the preferred form of construction, I do not wish to limit myself to the precise details of structure shown, but desire to avail myself of such variations and modifications as may come within the scope of the appended claims.

Having thus described my invention, what I claim as new and desire to secure by Letters Patent is:

1. A door check for preventing undue opening of a door swingably mounted on a stationary structure comprising: a bracket mounted on

said stationary structure; a link pivotally mounted at one of its ends to said bracket; a connecting plate pivotally connected at one of its ends to the opposite end of said link; a 5 second link of greater length than said first link and pivotally connected at one of its ends to the opposite end of said plate; and a bracket fixedly mounted on said door and pivotally connected at the opposite end to said longer link, the pivotal 10 points of said links and plate assuming a straight line position just prior to the authorized limit of opening of the door.

2. A door check for preventing undue opening of a door swingably mounted on a stationary 15 structure comprising: a bracket mounted on said stationary structure; a link pivotally mounted at one of its ends to said bracket; a connecting plate pivotally connected at one of its ends to the opposite end of said link; a second link of 20 greater length than said first link and pivotally connected at one of its ends to the opposite end of said plate; a bracket fixedly mounted on said door and pivotally mounted at the opposite end to said longer link; the pivotal points of said 25 links and plate assuming a straight line position just prior to the authorized limit of opening of the door; and a gripping member mounted on said plate and projecting outwardly therefrom.

3. A door check for preventing undue opening 30 of a door swingably mounted on a stationary structure comprising: a bracket mounted on said stationary structure; a link pivotally connected at one of its ends to said bracket; a connecting plate, said link being pivotally connected at its 35 opposite end to one end of said connecting plate; a second link of greater length than said first link and pivotally connected at one of its ends to the opposite end of said connecting plate; a doubled-over portion on said connecting plate 40 folded inwardly to overlie the edges of said links and serve as an abutment therefor; a bracket mounted on said door, the opposite end of said second link being pivotally connected to said bracket; said doubled-over portion of the connecting plate being angularly turned and 45 doubled upon itself to provide a gripping mem-

ber; and the pivotal points of said links and plate assuming a straight line position just prior to the authorized limit of opening of the door.

4. A door check for preventing undue opening 5 of a door swingably mounted on a stationary structure comprising: a bracket mounted on said stationary structure; a link pivotally connected at one of its ends to said bracket; said link being angularly turned intermediate its ends; a connecting plate, the opposite end of said link being pivotally connected to one end of said connecting plate, a second link of greater length than 10 said first link and bent intermediate its ends to provide an elongated arcuate portion extending angularly to the rest of the body and pivotally connected at one of its ends to said plate; and a bracket mounted on said door and pivotally connected to the opposite end of said second link, the pivotal points of said links and plate 15 assuming a straight line position just prior to the authorized limit of opening of the door.

5. A door check for preventing undue opening 20 of a door swingably mounted on a stationary structure, comprising: a bracket mounted on 25 said stationary structure; a link pivotally connected at one of its ends to said bracket; said link being angularly turned intermediate its ends, a connecting plate, the opposite end of said link being pivotally connected to one end of said connecting plate; a second link of greater length 30 than said first link and bent intermediate its ends to provide an elongated arcuate portion extending angularly to the rest of the body and pivotally connected at one of its ends to said 35 plate; a bracket mounted on said door and pivotally connected to the opposite end of said second link, said plate having a doubled under portion overlying the edges of said link at their points of pivotal connection for providing an 40 abutment therefor, gripping means carried by said plate; and the pivotal points of said links and plate assuming a straight line position just prior to the authorized limit of opening of the door.
